COMMUNION SET PORTFOLIO

Otto Mayer, Lake Carmel, N.Y.

Application September 14, 1959, Serial No. 57,525

Term of patent 14 years

(Cl. D87—3)

FIG.1

Figure 1 is a perspective view, in open condition, of a communion set portfolio, showing my new design;

Figure 3 is a view similar to Figure 2 showing one flap of the article in completely closed condition; and

I claim:

The ornamental design for a communion set portfolio, substantially as shown.
